[57] **CLAIM**

The ornamental design for a combined lectern and display calculator, substantially as shown and described.

DESCRIPTION

FIG. 1 is a right front perspective view of a combined lectern and display calculator showing my new design, the parts shown in dotted lines being for illustrative purposes only;

FIG. 2 is a top plan view thereof;

FIG. 3 is a front elevation view thereof, the parts shown in dotted lines being for illustrative purposes only;

FIG. 4 is a right side elevation view thereof, the left side being a mirror image of the right side; and

FIG. 5 is a rear elevation view thereof.

FIG. 5.

FIG. 1.

FIG. 2.

FIG. 3.

FIG. 4.
